DESIGN FOR LACE

Morris Taub, New York, N. Y.

Application March 12, 1937, Serial No. 68,127

Term of patent 3½ years

To all whom it may concern:

Be it known that I, Morris Taub, a citizen of the United States of America, residing in Manhattan, county and State of New York, have invented a new, original, and ornamental Design for Lace, of which the following is a specification, reference being had to the accompanying drawing, forming part thereof, wherein, the figure is a plan view of a piece of lace showing my new design.

The design consists of individual units of alternating color in combination with a solid colored border at the upper and lower edges as shown.

I claim:

The ornamental design for lace, substantially as shown and described.

MORRIS TAUB.
